UNITED STATES PATENT OFFICE.

PLINY F. HODGES, OF MASSILLON, OHIO, ASSIGNOR OF PART OF HIS RIGHT
TO EDWIN BAYLISS, JAMES O. BROWN, AND FRANCIS T. LOMONT, OF
SAME PLACE.

IMPROVEMENT IN BINDERS' ATTACHMENTS FOR HARVESTERS.

Specification forming part of Letters Patent No. 151,288, dated May 26, 1874; application filed
March 14, 1874.

To all whom it may concern:

Be it known that I, PLINY F. HODGES, of Massillon, in the county of Stark and State of Ohio, have invented certain new and useful Improvements in Reaping-Machines, of which the following is a full, clear, and exact description, reference being had to the accompanying drawing, which represents a perspective view of so much of a harvesting-machine as is necessary to show my improvement.

My invention relates to that class of reaping-machines employing a horizontal endless-apron platform, and an elevator apron or aprons, for conveying the grain to the binders riding upon the machine, and more particularly to that class of machines in which the horizontal and elevator aprons are mounted upon a hinged platform or cutter frame, while the binders and binders' platform are mounted upon the main or wheel frame; and has for its object the adaptation of the raking and binding attachment to be applied to a two-wheel hinged-bar mower, whereby the machine is adapted to be used both for mowing and reaping, or what is known as a combined machine. The invention consists in combining the upper swinging end of the elevator-frame, which is mounted upon the hinged platform-frame, with the binders' table on the main or wheel frame by an extensible guiding-apron, which will permit the vibrations of the elevator in conforming to the movements of the platform-frame, relatively to the main frame and binders' table, while, at the same time, said apron at all times crosses the space intervening between the swinging elevator-frame and the binders' table, for guiding the grain from the elevator to the table and effectually preventing the escape of the grain between them in its passage, as hereinafter described.

In the accompanying drawing, A represents the main frame mounted upon two driving-wheels, B B. C represents the inner end of the platform-frame, which is hinged by means of a coupling-frame, D D D', to the main frame, the arms D D being hinged, one in front and

the other in rear of the wheels, at one end to the main frame, in line or nearly in line with the crank-shaft, and at the other to the platform-frame, to permit the free vibration of the latter in mowing; or the rear bar D may be removed when the machine is used as a mower, and the cutting apparatus supported by the forward arm and the oblique or diagonal brace D'. The platform-frame C is provided at its inner end with arms C¹, rigidly connected thereto, and extending inward to about midway of the width of frame A, where they are suspended from hooks a on the main frame by means of chains c, which may be readily adjusted for holding the inner end of the platform-frame at any desired elevation. E represents a binders' stand or platform on the main frame over the gearing, and E¹ is a binders' table mounted on corner upright e on the frame A, said table being perforated at E² to accommodate the legs or persons of the binders standing on the platform E, or sitting on the table E¹. The inner or grain side of this table E is provided with upright lugs or ears f, one at each end, in which is mounted the shaft of a longitudinal roller, F, to which is attached one end of an apron or canvas, G, which extends outward and upward, and is connected at its opposite end to a rod or roller connected with the upper end of the elevator-frame C², which is mounted upon and vibrates with the hinged platform-frame C. The elevator, one of the upper rollers of which is shown at C³, and which may be of any usual or preferred construction, is so arranged, relatively to the apron G, that the grain, as it is discharged from the upper end of the elevator, falls upon the upper inclined face of, and is guided by, said apron in its descent to the binders' table E¹. To provide for the vibration of the elevator with the hinged platform-frame, relatively to the main or wheel frame A, the roller F, either directly or through a pulley on the end of its shaft, and a cord, h, is connected with a spring, H, (or weight,) in such manner as that the tension of the spring serves, through the cord h, to rotate the roller F, thus wind-

ing and taking up any slack in the apron G consequent upon the variations in the distance between the vibrating upper end of the elevator and the binding-table, and keeping the apron always in the best shape for the delivery of the grain from one to the other, while effectually preventing the escape of any grain between them. The roller and spring may be applied at the elevator end of the apron, if preferred.

The same result may be accomplished by the employment of a divided apron of wood or metal, one leaf or panel of which is hinged to the table E¹, and the other to the elevator-frame C², the one connected with the elevator-frame overlapping and sliding upon the one connected with the table E¹, to accommodate the vibration of the platform and elevator-frame.

These overlapping ends may be connected by any suitable arrangement, such as loops or slots, and through headed bolts or pins to per-

mit them to slide by each other freely, while the hinges at each end permit this apron to freely accomodate itself to the constantly-varying angle of relation between the top of the elevator-frame and the binders' table. This extensible apron may be used to connect the elevator on a rigid-frame machine, with a binders' table mounted on an outside hinged binders' carriage or frame.

Parts of the machine not particularly described may be constructed in any usual or preferred manner.

Having thus described my invention, what I claim as new, and desire to secure by Letters Patent, is—

The extensible delivery-apron in combination with the grain-elevator frame and binders' table, substantially as described.

PLINY F. HODGES.
